UNITED STATES PATENT OFFICE.

HENRY E. STAGER, OF CHICAGO, ILLINOIS.

AUTOMATIC VALVE.

SPECIFICATION forming part of Letters Patent No. 708,179, dated September 2, 1902.

Application filed August 23, 1901. Serial No. 73,078. (No model.)

To all whom it may concern:

Be it known that I, HENRY E. STAGER, a citizen of the United States, residing at Chicago, in the county of Cook and State of Illinois, 5 have invented certain new and useful Improvements in Automatic Valves, of which the following is a specification.

The object of this invention is the production of an automatic valve for steam-radiators that while permitting the escape of cold air from the radiator wholly prevents the escape of water or the continued escape of steam.

A further object of this invention is to render such a valve simple, cheap, and durable and not easily tampered with or gotten out of order.

In the accompanying drawings, Figure 1 is a vertical central section through a valve embodying the features of my invention, showing the parts in position to permit the escape of cold air. Fig. 2 is a similar view showing the parts in position to prevent the escape of steam. Fig. 3 is a similar view showing the parts in position to prevent the escape of water from the valve. Fig. 4 is a transverse section on dotted line 4 4 of Fig. 3. Fig. 5 is a view of the key with which the expansible pencil of the valve is adjusted.

Like letters of reference indicate corresponding parts throughout the several views.

In the production of this valve I provide the bottom A, in cup form, having the integral hollow externally-threaded plug A' extending from its side and communicating with its interior. By means of this plug the valve is connected with the radiator. The inner side of the cup A is provided with the integral vertical guide-ribs A² for a purpose to 35 be hereinafter mentioned, and its upper edge has the internal screw-threads A³. An air-bell B is adapted to sit within the cup A, being held in position centrally therein by the vertical guide-ribs A². This air-bell is formed, 40 preferably, from sheet-copper, and its upper end is provided with the spur B'. The bell B is so placed within the cup A that air or steam entering said cup through the hollow plug A' may pass upward beside said bell 45 without disturbing it.

A tubular shell C, formed, preferably, from seamless brass tubing, is provided with the

screw-threads C' and C² at opposite ends of said shell, the threads C' being adapted to engage with the corresponding screw-threads 55 A³ of the bottom cup A. A cap D, internally screw-threaded to correspond with the screw-threads C² of the shell C, is secured by said screw-thread connection to the upper end of said shell. This cap is provided with an integral central tubular body portion D', provided at its lower end with the opening D², coinciding with and adapted to receive the spur B' of the air-bell B, also with the air-escape opening D³, extending through the side 60 of said tubular body portion D'. The upper end of said tubular body portion is internally screw-threaded and is provided with a correspondingly screw-threaded closure D⁴, having the two depressions D⁵ in its face for the insertion of the points of a suitable key. The face of the opening D² within the tubular body portion D' is surrounded with a raised rim D⁶ as a seat for the expansible thermal closure to be next described. 70

E is a pencil composed of an expansible composition held within the tubular body portion D' by its supporting screw-threaded plug E', which latter is externally screw-threaded to correspond with the internal screw-threads 80 of said body portion D'. The plug E' has a socket E² formed in its end for the reception of the end of the pencil E, and in its opposite side has the two depressions E³, adapted to receive the points of the operating-key hereinbefore mentioned and to be next described. F is said operating-key, having the two points F', adapted to enter the openings D⁵ of the closure D⁴ and the depressions in the plug E'. The closure D⁴ and the plug E' are provided 85 with depressions, and thus adapted to be operated by the key F in order that the valve 90 shall not be tampered with and its proper adjustment disturbed.

In use this automatic valve is secured to a 95 radiator in the usual manner by means of the screw-threaded plug A' and its parts properly adjusted. When steam is admitted to the radiator, the cold air in the pipes is forced through said hollow plug A' into the cup A 100 and the shell C through the opening D² into the tubular body portion D', escaping to the outer air through the opening D³. When the cold air has all been driven from the radiator,

steam enters the tubular body portion D' of the valve, and the heat of said steam expands the composition pencil E, causing the end of the pencil to fit firmly against the 5 raised rim D⁶, surrounding the opening D² in the bottom end of the tubular portion D', closing said opening and preventing further escape of steam therethrough. The heat of the steam within the shell C is sufficient to 10 maintain the heat of the pencil E and prevent its contraction to uncover the opening D². When, however, from any cause said pencil becomes sufficiently cool to contract and withdraw from said rim D⁶, cold air first 15 escapes through the opening D² until steam is again brought within the shell C and the tubular body portion D', and the pencil again contacts the rim D⁶ and closes said opening D². If water is forced through the hollow 20 plug A' into the cup A, it rises within the cup A until it buoys up the air-bell B therein. When said air-bell is raised sufficiently, the spur B' of the air-bell B enters the opening D² of the tubular body portion D' and prevents 25 the escape of said water from the shell C. The shell C acts as an air-chamber, air being compressed within its upper end by the incoming water, and said air-pressure tends to force the water from said cup A. The position 30 of the expandible pencil E is made adjustable with relation to the annular rim D⁶, against which it closes, by turning the threaded plug E' in the internal screw-threads of the tubular body portion D' by means of the key F. The air-bell, as will readily be seen, 35 acts as a float.

I claim as my invention—

1. In a valve for steam-radiators, in combination, an outer shell or casing having an inlet-opening and an air-escape opening; a tubular body portion formed integral with one of the ends of said shell or casing, projecting into the interior thereof and being provided at its inner end with an opening; an air-bell 40 within said outer casing, having a projection adapted to close the opening in said body portion; and a pencil expandible by heat, mounted in said body portion and adapted to close the opening therein.
2. In a valve for steam-radiators, in combination, a bottom cup provided with a screw-threaded plug for connecting said valve with a radiator, said plug having an opening extending therethrough and communicating 45 with the interior of the bottom cup; a casing-shell secured to said bottom cup; an air-bell in said bottom cup and said casing-shell, the bottom of said air-bell being normally below the mouth of the opening through said plug; a projection on said air-bell; a cap having a screw-thread engagement with the upper end of said casing-shell; a tubular body portion 50 formed integral with said cap and extending into said casing-shell, said body portion having an opening in its lower end adapted to be closed by the projection on said air-bell; a raised rim around the opening in said body portion; a pencil expandible by heat, adapted when expanded to contact said raised rim to close said opening; a plug in said tubular body portion, for supporting said pencil, said plug having a screw-thread engagement with the body portion; and a closure for the upper end of said tubular body portion.

HENRY E. STAGER.

L. L. MILLER,
ALBERT U. STAGER.

portion formed integral with one of the ends of said casing-shell, projecting into the interior thereof and being provided at its inner end with an opening adapted to be closed by the projection on said air-bell; and a pencil 65 expandible by heat, mounted in said body portion and adapted to close the opening therein.

3. In a valve for steam-radiators, in combination, a bottom cup provided with a screw-threaded plug for connecting said valve with a radiator, said plug having an opening extending therethrough and communicating with the interior of the bottom cup; a casing-shell secured to said bottom cup; an air-bell in said bottom cup and said casing-shell, the 70 bottom of said air-bell being normally below the mouth of the opening through said plug; a projection on said air-bell; a cap secured to the upper end of said casing-shell; a tubular body portion supported within said casing-shell by said cap, said body portion having an opening in its lower end adapted to be closed by the projection on said air-bell; a pencil expandible by heat, also adapted to close said opening; a plug in said tubular body portion, for supporting said pencil, said plug having a screw-thread engagement with the body portion; and a closure for the upper 75 end of said tubular body portion.

4. In a valve for steam-radiators, in combination, a bottom cup provided with a screw-threaded plug for connecting said valve with a radiator, said plug having an opening extending therethrough and communicating with the interior of the bottom cup; vertical 80 guides upon the inner walls of said bottom cup; a casing-shell having a screw-thread engagement with said bottom cup; an air-bell in said bottom cup and said casing-shell, the bottom of said air-bell being normally below 85 the mouth of the opening through said plug; a projection on said air-bell; a cap having a screw-thread engagement with the upper end of said casing-shell; a tubular body portion formed integral with said cap and extending 90 into said casing-shell, said body portion having an opening in its lower end adapted to be closed by the projection on said air-bell; a raised rim around the opening in said body portion; a pencil expandible by heat, adapted 95 when expanded to contact said raised rim to close said opening; a plug in said tubular body portion, for supporting said pencil, said plug having a screw-thread engagement with the body portion; and a closure for the upper 100 end of said tubular body portion.
